(57) CLAIM

The ornamental design for a shoe sole with flower design, as shown and described.

DESCRIPTION

FIG. 1 is a bottom perspective view of a shoe sole with flower design, in accordance with my new design;

FIG. 2 is a rear perspective view thereof;

FIG. 3 is a right side view thereof;

FIG. 4 is a left side view thereof;

FIG. 5 is a rear view thereof;

FIG. 6 is a bottom view thereof;

FIG. 7 is a front perspective view thereof; and

FIG. 8 is a front view thereof; and,

FIG. 9 is a top view thereof.

The broken lines depict environment and form no part of the claim. The surfaces between the solid line subject matter are part of the broken line showing of a shoe and form no part of the claim.

1 Claim, 9 Drawing Sheets
